ATTORNEY

UNITED STATES PATENT OFFICE.

ROBERT H. WORRELL, OF STATESBURG, WEST VIRGINIA.

METAL TIE AND RAIL-FASTENER.

1,341,609.

Specification of Letters Patent.

Patented May 25, 1920.

Application filed February 3, 1920. Serial No. 355,942.

To all whom it may concern:

Be it known that I, ROBERT H. WORRELL, a citizen of the United States, residing at Statesburg, in the county of Raleigh and 5 State of West Virginia, have invented new and useful Improvements in Metal Tie and Rail-Fasteners, of which the following is a specification.

This invention relates to railroad devices 10 and has for its object the provision of a metallic tie upon which are mounted rail engaging members whereby the rails may be held firmly and securely thereon without any necessity for the employment of spikes 15 or other accessories.

An important object is the provision of a tie and rail fastener of this character in which the rail engaging members are pivotally mounted so that they may, when the 20 occasion arises, be swung out of engagement with the rail.

An additional object is the provision of a structure of this character which will be very simple and inexpensive in manufacture, 25 highly efficient in use, durable in service, and a general improvement in the art.

With the above and other objects and advantages in view the invention consists in the details of construction to be hereinafter 30 more fully described and claimed, and illustrated in the accompanying drawing in which—

Figure 1 is a plan view of my tie and rail fastening device,

Fig. 2 is a longitudinal sectional view therethrough, and

Fig. 3 is a perspective detail view of one end of one of the rail engaging members.

Referring more particularly to the drawings, the numeral 10 designates a tie which is formed of metal and which is trough-shaped in cross section, as shown. It is understood that if desired the tie might be made rectangular in cross section. This tie 45 is adapted to support rails A and in order that the rails may be secured upon the tie I provide at each end of the tie a pair of rail engaging members 11 and 12, 11 being the outer and 12 the inner. The outer members 11 are formed from metal and are made in elongated shape having substantially the same width as the tie. Each of these members is provided with a circular depressed portion 13 which is pivotally mounted upon 50 the tie by a suitable bolt or the like 14. The remainder of the member does not bear

upon the tie. Formed at the outer ends of the tie are upwardly extending projections 15 formed by stamping the body of the tie upwardly from the underside and each 60 member 11 has formed therein at its outer end a correspondingly shaped depression 16 of partially spherical shape adapted to engage the projection 15. When such engagement is effected it will be seen that the members 11 will properly engage the bases of the rails A.

The inner members 12 are substantially the same in construction as the outer members 11 except that they are longer though 70 of the same width. Each member 12 is formed as an elongated plate resilient in nature provided with a circular depression 17 which is pivotally connected with the tie, as shown at 18, as by means of a suitable bolt or rivet. Each member 12 has also formed therein at its underside a depression 19, formed by stamping, and engageable over a corresponding projection 20 formed by stamping the tie from its 80 underside. A longitudinal rib 21 extends from the depression 17 to the depression 19 and serves to strengthen the member. At its free end, that is the end adjacent the projection 20, each member 12 is provided 85 with an inverted U-shaped hook or partial loop 22 within which may be engaged a suitable tool for prying the member 12 so as to engage the depression 19 upon the projection 20 in order to bring the other end of 90 the member into proper engagement with the base of the rail secured.

In order that the depression 19 may be properly guided onto the projection 20, I provide the inner end of each member 12 95 with depressions 23 leading from the side edges of the member to the depression 19. When the member 12 is swung upon its pivot either depression 23 will engage and slide over the projection 20 until the depression 19 engages upon the projection 20.

From the foregoing description and a study of the drawing it will be apparent that I have thus provided a very simply constructed tie rail fastener which will be 105 extremely efficient in use, which will permit rapid laying of a track, and which will be highly efficient and durable.

While I have shown and described the preferred embodiment of my invention it is 110 of course to be understood that I reserve the right to make such changes in the form,

construction, and arrangement of parts as will not depart from the spirit of the invention or the scope of the subjoined claims.

Having thus described my invention, I 5 claim:

1. In combination, a tie, rails seating upon the tie, and rail members carried by the tie including a pair of plate members pivoted upon the tie outwardly of the rails and each 10 having one end engaging the base of a rail, an upwardly extending depression formed in the outer end of each of said plates, an upwardly extending projection formed upon the tie and engageable with said depression, 15 and a pair of rail engaging members disposed upon the tie inwardly of the rail, each of said last named members including an elongated plate pivoted upon the tie and having one end engageable with the base of 20 a rail and having its other end formed with an upwardly extending loop member, an upwardly extending depression formed in the underside of each of said last named members adjacent said loop members, up- 25 wardly extending projections formed in the tie and engageable by said last named depression, a longitudinal rib formed in each of said last named members and terminating at said last named depressions, and guide 30 depressions formed in each of said last named members and extending from the outer edges thereof to said last named de- pressions.

2. In combination, a tie, rails seating upon the tie, and rail fastening means carried by 35 the tie and including a pair of plate members pivoted on the tie outwardly of the rails and each having one end engaging the base of a rail, mating depressions formed in the outer ends of said plates and the ties beneath said 40 plates, and a pair of rail engaging members pivoted upon the tie inwardly of the rails, each of said last named members including an elongated plate having one end engageable with the base of a rail and the other 45 ends of said second named members and the tie therebeneath being formed with mating depressions.

3. In combination, a tie, rails seating upon the tie, and rail fastening means carried by 50 the tie comprising a pair of plate members pivoted upon the tie outwardly of the rails and each having one end engaging the base of a rail, said plate members and the tie being provided with mating depressions, and 55 a pair of rail engaging members pivoted upon the tie inwardly of the rails and each including an elongated plate having one end engageable with the base of a rail and its other end formed with an upwardly extending loop member, said last named members and the tie therebeneath being formed with 60 mating depressions.

In testimony whereof I affix my signature.

ROBERT H. WORRELL.
